SANDING OR RUBBING ATTACHMENT

Samuel Davis Robins, Lawrence, N. Y., assignor
to Du-Fast, Inc., New York, N. Y., a corporation
of New York

Application July 26, 1947, Serial No. 763,810

9 Claims. (Cl. 51—170)

1

This invention relates to certain new and useful improvements in rubbing machines and means for stabilizing the motion of eccentrically vibrated bodies and especially provides an attachment for portable or hand drilling machines to enable their use as rubbing machines for surface smoothing and/or finishing in the wood working, cabinet making, boat building and allied arts. The invention finds application also in the stabilizing of the motion of eccentrically vibrated screens, such as are used for sifting and for cleaning coal, coke and the like.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate a preferred embodiment of the invention, and together with the description, serve to explain the principles of the invention.

In the rubbing machine art, as well as in the sifting, and screening machine art, it has long been common practice to actuate the so-called "live frame" of the machine by means of a single counterbalanced eccentric actuating the frame substantially at its center-of-gravity. Such practice is typified by U. S. Patents Nos. 1,693,940 and 1,957,790, for example. It has also been common practice to actuate the live frame by means of the centrifugal reaction of the counterweight alone in which case the mechanical eccentric is omitted and the driving torque supplied through a flexible shaft or belt as in U. S. Patents Nos. 2,032,382 and 2,270,309, for example.

In all such cases, however, some means of "stabilizing" the motion of the vibrating live frame, be it screen or rubbing shoe, is employed. In most cases stabilization is effected by some form of flexible stabilizing means spaced beyond the center-of-actuation, flexibly connecting the "live frame" to the "dead frame" and permitting the desired reciprocatory or gyratory movement, as the case may be, of the live frame with respect to the dead frame to take place. In the case of the gyrating movement, moreover, such stabilizing means oppose any large rotation of the live frame with respect to the dead frame. Various flexible stabilizing means for the above purposes are typified in U. S. Patents Nos. 1,741,145,

5 2,032,382, 2,113,694, 2,200,724 and 2,258,217, for example and it is an object of this invention to provide a new and improved form of flexible stabilizing means for eccentrically vibrated bodies.

10 Symmetrically disposed flexible stabilizers, such as are disclosed in U. S. Patents Nos. 2,032,382, 1,693,940, 2,200,724, 2,270,309 and 2,334,172, for example, are truly permissive in their function in that they allow a truly gyratory movement of the live frame to take place, but they fail to be controlling in the sense that such flexible means cannot prescribe a circular orbit throughout the live frame under conditions where outside forces may disturb the gyratory orbits or 15 may tend to place heavy rotational loads on the live frame as a whole. That is, they do not have "position" stability. Such outside forces are commonly present in machines of all the classes referred to herein and do have deleterious effects.

15 Another object of this invention therefore is to provide "position" stabilization for eccentrically gyrated bodies without recourse to the expansive mechanical stabilizing means which also are common in these arts. Position stabilization comes under one of three common categories, to wit, geared eccentrics, as exemplified by U. S. Patent No. 2,395,537; follower cranks (geared or not) as exemplified by U. S. Patent No. 2,247,- 20 993; and, pantographs. All of these accomplish not only the permissive function of the cheap flexible stabilizer but serve the added function of actually eliminating a general rotation, either oscillatory or otherwise, of the live frame with respect to the dead frame. The first two types of stabilizers, namely, geared eccentrics and follower cranks are objectionable on at least three grounds. They involve rotating parts which not only involve extra cost but additional wear and sealing devices to exclude dirt. They also require great precision to ensure perfect timed relation to the master eccentric and this involves extra cost. Pantograph means of position stabilization is to be preferred if for no other reason than 25 because no precise relation is called for in the assembly of the parts of the pantograph nor in the application of the pantograph to the machine.

30 It is therefore another object of this invention to enable position stabilization, on the pantograph principle, of gyratory bodies through the provision of flexible elements only and without the use of mechanical journals either rotating or oscillatory to the end that no important wear can occur, no undue attention for maintenance or

lubrication will be needed and the device will be practically immune to the presence of dirt, liquid, or abrasives.

A further object of this invention is to enable the utilization of so-called "hand" or "portable" general purpose drilling machine as the power unit of an eccentrically vibrated portable or hand rubbing machine, through the provision of the improved motion stabilizing means of this invention. In this connection, it will be understood that portable rubbing machines, as taught by the prior art, are many and varied in type. In particular, the portable or hand type vibratory sanders are, in general, highly complex single purpose mechanisms producible only at a high cost of manufacture. They embody relatively high powered power units and the vibratory motion of the "live" frame or shoe is characterized by a relatively short stroke, e. g. $\frac{1}{4}$ inch or less, at a very high rubbing speed. On the other hand, general purpose, low cost, hand drilling machines such as the conventional $\frac{1}{4}$ inch electric drilling machine commonly found in the "home workshop" are characterized by a relatively low power, for example, a 1.5-2.5 ampere rating and by a relatively low chuck speed in the range, for example, of 1000 to 2500 revolutions per minute. This low chuck speed requires that if the drill is to be used to eccentrically vibrate a rubbing shoe, a long stroke of the rubbing shoe in the order of $\frac{1}{2}$ inch, for example, is required in order to obtain a practically useful rubbing speed. Position stabilization of the rubbing shoe through the use of known flexible stabilizing means such as the rubber skirts, rings and the like, common in the art, would not do for this for, if the rubber skirt, for example, were flexible enough to permit the required large stroke and yet not break down, it would allow the live frame or shoe to rotate relative to the dead frame, or to deflect. Such rotation would inevitably result in overstressing of the flexible stabilizing means as deflection of it due to vibration, plus that due to rotation, builds up. On the other hand, if a rubber skirt stabilizer were used and made strong enough so as not to go to pieces under the conditions of severe stress reversal, then the heat loss would be large and the power drain on the hand drill would be too high, thus making use of the rubbing shoe a practical impossibility on such drills. It is therefore another object of this invention to provide a new, useful and improved rubbing machine particularly adapted for use in surface sanding in the woodworking and allied arts, and to provide a new and useful rubbing attachment for low cost electric hand drills, to the end that the "home workshop" in particular may be provided, through the medium of such attachment, with both drilling machine and rubbing machine in one low cost, dual purpose tool.

In the accompanying drawings in which like numbers refer to like parts throughout the several views:

Figure 1 is a perspective view of a preferred embodiment of this invention as applied to a sander attachment for low cost electric hand drills, the view showing the hand drill (less chuck) and the rubbing attachment, including actuating eccentric, in exploded relationship, ready for assembly into a complete rubbing machine unit, the drill and detached chuck of the drill being shown in dash-dot outline;

Figure 2 is a view in vertical section along the medial longitudinal plane of the embodiment shown in Figure 1, the view showing the rubbing attachment and hand drill in assembled relation-

ship with the rubbing head in thereby displaced position, the hand drill (less chuck) being shown in dotted outline;

Figure 3 is a view in top plan of the embodiment shown in Figure 1 omitting the driving eccentric for the rubbing shoe in order to expose underlying parts, the rubbing head being shown in normal undisplaced position;

Figure 4 is a view in side elevation of the embodiment of Figure 1;

Figure 5 is a view in end elevation of the embodiment shown in Figure 1; and,

Figure 6 is a fragmentary view in section of a modified form of eccentric actuating means and its connection to the rubbing shoe of the embodiment of Figure 1.

In general, the motion of an eccentrically vibrated body may be positionally stabilized in accordance with this invention through the provision of a novel system of stabilizing link members flexibly connecting the live frame to the "dead" frame and permitting a high degree of freedom of movement of the live frame in translation while preventing its rotation relative to the dead frame.

In accordance with the preferred illustrative embodiment of this invention, an intermediate frame is disposed between the live frame and the dead frame and is flexibly connected to the respective frames by separate systems of stabilizing link members, disposed at right angles to each other.

The system of dead frame link members operates to prevent any rotation of the intermediate frame relative to the dead frame while permitting a to-and-fro substantially linear motion of translation of the intermediate frame substantially parallel to the dead frame, in one direction only. The system of live frame link members likewise operates to prevent any rotation of the live frame relative to the intermediate frame while permitting a to-and-fro substantially linear motion of translation of the live frame substantially parallel to the intermediate frame, in a direction at right angles only to the permitted direction of movement of the intermediate frame. Thus, relative rotation of the live frame and the dead frame is wholly prevented by the torsional rigidity of the stabilizing system as a whole while the respective motions of the live frame and intermediate frame may be compounded to cause the live frame to move in a motion of curvilinear translation relative to the dead frame.

Means are provided for actuating the live frame through the application thereto of a radial force of preferably constant magnitude but of constantly changing direction to impart thereto a motion of translation which is preferably circular.

Advantageously, moreover, the dead frame may be constructed and arranged for releasable locking engagement with the frame, motor housing or other fixed portion of a portable electric drilling machine so as to provide a rubbing attachment combinable with the drilling machine to form the novel and improved rubbing machine of this invention. In such case, the usual chuck of the drill is removed and is replaced by the actuating means above-mentioned for engaging and eccentrically vibrating the live frame in statically and dynamically counter-balanced relationship. In such case also, the live frame is suitably fashioned to serve as a rubbing shoe or head having provision for releasably securing thereto a layer of rubbing material such, for example, as a sheet of sand paper or other abra-

sive material, by means of certain novel quick release fastening devices of this invention.

It will be understood that the foregoing general description and the following detailed description as well are exemplary and explanatory of the invention but are not restrictive thereof.

Referring now more particularly to the embodiment of this invention shown in Figures 1 to 5 of the accompanying drawings, a dead frame 1 is disposed in spaced, parallel or substantially parallel relation to a live frame 2. An intermediate frame 3 is disposed substantially midway between the live frame and dead frame in parallel or substantially parallel relation thereto. The intermediate frame 3 is flexibly connected to the dead frame 1 by a system of normally parallel link members 4 and is flexibly connected to the live frame by a system of normally parallel link members 5, disposed at right angles to the system of link members 4.

The link members 4 and 5 as here preferably embodied are each constituted by a short strip of flexible material such, for example, as power belting material capable of undergoing a practically infinite number of flex stress reversals over a pulley of small diameter, e. g. $\frac{1}{2}$ inch, without failure.

The intermediate frame 3 as here preferably embodied is of rectangular or substantially rectangular shape and comprises parallel side and end rails 6 and 7, respectively, preferably of metal, forming a rigid yet light weight open structure.

Each of the end rails 7 serves as a terminal fitting fashioned to receive and firmly grip an end of one of the link members 4 whose other end is likewise received and firmly gripped by one of a pair of terminal fittings 8 each likewise fashioned for the purpose and fixedly secured to the dead frame 1 at its ends in parallel relation to each other and to said end rails 7 so that the link members 4 will normally parallel each other at the frame ends. Thus, by reason of the flexible nature of the link members 4 and their parallel arrangement, the intermediate frame 3 is capable of substantially linear to-and-fro movement parallel to the dead frame in one direction only, but is substantially completely immobilized against rotation relative thereto.

Each of the side rails 6 also serves as a terminal fitting fashioned to receive and firmly grip an end of one of the link members 5 whose other end is likewise received and firmly gripped by one of a pair of terminal fittings 9 each likewise suitably fashioned for the purpose and fixedly secured to the live frame 2 at its sides in parallel relation to each other and to said end rails 7 so that the link members 5 will normally parallel each other at right angles to the link members 4. Thus, by reason of the flexible nature of the link members 5 and their parallel arrangement, the live frame 2 is capable of substantially linear to-and-fro movement parallel to both the intermediate frame 3 and the dead frame 1 in one direction only which is at right angles to the permitted direction of movement of the intermediate frame. Moreover, it will be apparent that the open construction of the frame-link system offers complete freedom of view into the confines of the enclosure thus formed which is of particular advantage as will more fully appear hereinafter.

Means are provided for actuating the live frame 2 through the application thereto of a radial force of preferably constant magnitude

but of constantly changing direction, substantially at its center-of-gravity to impart to the live frame a motion of translation which may be reciprocatory but is preferably an orbital motion of circular translation. The actuating means as here preferably embodied comprises a crank member 10 having a stub shaft 11 adapted to be connected to a suitable prime mover, a crank pin 12 at one side of the stub shaft, and a counterweight portion 13 at the opposite side.

The crank member 10 as shown in Figure 2, is journalled to the live frame 1 by means of suitable anti-friction journal means such as the ball-bearing unit 14 in whose inner raceway the crank pin 12 is snugly but not tightly received. The tip portion of the crank pin is of a configuration which is preferably spherical as shown to permit a degree of self-aligning rocking action of the crank pin in the inner raceway of the bearing unit so that any minor angular displacement of the live frame will not be transmitted directly to the crank member. Moreover, the crank portion 12 and the journal unit 14 are disposed and arranged with respect to the live frame so that the radial thrust force of the crank portion will be applied to the live frame substantially in the horizontal plane of the center-of-gravity of the live frame and preferably so as to make the center-of-gravity and center-of-actuation of the live frame closely coincident, within practical limitations of construction.

The counterweight portion 13 of the crank member is likewise of a mass and arrangement affording optimum static and dynamic balance of the counterweight portion and live frame about the rotational axis of the stub shaft 11. Moreover, in order to minimize dynamic unbalance caused by the creation of a couple tending to cause whipping of the stub shaft 11, the counterweight portion is concentrated on the crank pin side of the crank member so as to be close to the live frame substantially in the bearing plane.

It will be evident that the rotation of the crank member 10 on the rotational axis of the stub shaft 11 coupled with the action of the stabilizing system will impart to the live frame 2 a motion of translation in a circular orbit, assuming the dead frame 1 to be held fixedly. The diameter of the orbit will obviously be determined by the "throw" of the crank portion 12, and in the application of this invention as a rubbing attachment for portable electric drilling machines, a throw of approximately one quarter of an inch has been determined to be advantageous in order to obtain an efficient rubbing speed.

For such application and in accordance with the preferred embodiment of this invention as illustrated in Figures 1 to 5 inclusive, the dead frame 1 is suitably constructed for releasable attachment to the barrel (motor housing) or other fixed portion of the drilling machine. Preferably, the dead frame, which may be referred to for convenience as the attaching head, is provided with an aperture 16 designed to permit the insertion of the chuck end of a conventional electric hand drilling machine 17 such as is indicated in dotted outline in Figures 1 and 2, from which the chuck 18 (Figure 1) is removed and is replaced by the crank member 10 whose stub shaft 11 is preferably threaded, as shown, for releasable engagement with the chuck driving spindle of the drill, as indicated in Figure 2.

Means are provided for releasably firmly securing the attaching head 1 of the rubbing attachment to the drill. As here preferably embodied, a pair of fixed positioning lugs 19 carried by the attaching head 1 at one end of the aperture 16 are disposed to engage the barrel of the drill unit 17 at spaced points preferably in suitable apertures such as the series of cooling air ventilating apertures 20 disposed circumferentially of the drill motor housing. A movable clamping member 21 disposed in the aperture 16 at its opposite end is pivotally supported by and at one end of a clamping screw 22 which is in turn threadedly received in a lug 23 integral with the attaching head 1. Other positioning lugs 24 integral with the movable clamping member 21 are disposed to engage the drill unit 17 at spaced points as in the ventilating apertures 20. The clamping member 21 is of a configuration complementary to the surface portion of the drill housing which it is adapted to engage, as is the attaching head 1 at the opposite end of the aperture 16. Guide members 25 preferably integral with the clamping member 21 extend outwardly therefrom in sliding engagement with the attaching head and serve to maintain the clamping member in a generally upright position with respect to the attaching head. The pivotal connection of the clamping member to the clamping screw enables the former to accommodate itself to any slight irregularities in shape of the drill housing.

It will be apparent from the foregoing that the drill unit is adapted to be clamped in the aperture 16 between the attaching head 1 at one end of the aperture 16 and the screw actuated clamping member 21 at the other end. The positioning lugs 19 and 24 serve precisely to locate the rubbing attachment vertically as viewed in Figure 2 as a whole relative to the drill unit so that the crank pin 12 will be correctly positioned in the bearing unit 14 in the assembled relationship. It will be apparent also from a consideration of Figure 2, that in assembling the drill unit and rubbing attachment, a lateral displacement of the live frame or rubbing head 1 in an amount equal to the "throw" of the crank member 10 will be necessary. This displacement is shown in Figure 2 wherein the stabilizing link members 4 are shown in an extreme flexed position. Moreover, although the terminal fitting 8 of the link members 4 may be integral with the attaching head 1, they are preferably each provided at their respective opposite ends with attaching lugs 26 by which they are removably secured to the attaching head 1 by suitable fastening means such as the nut-bolt combination 27 shown. In this way, different attaching heads may be conveniently employed to adapt the attachment for use with different drilling machines.

The live frame or rubbing head 2 of the rubbing attachment, as here preferably embodied comprises a relatively stiff flat member 28 forming a pressure plate of rectangular contour in plan, as seen in Figure 3, having upstanding marginal stiffening flanges 29 at its opposite sides and curved upwardly and inwardly turned end portions forming sockets 30 in which the ends of a sheet 31 of sand paper or other rubbing material are adapted to be removably secured. Reinforcement of the plate member 28 is effected by a stiffening member 32 extending preferably from side-to-side of the pressure plate 28 and apertured to fit snugly over and around the bearing socket member 15 upon a circumferential

marginal base portion 33 providing a broad and ample support for the bearing socket 15 on the pressure plate 28. Fastening means 34 serve to hold the bearing socket in fixed position between the stiffening plate 32 and pressure plate 28 centrally of the latter. The stiffening plate 32 is offset at its opposite ends into engagement with the pressure plate 28 to which it is fixedly secured. It will be noted that the stiffening plate by reason of its spaced relation to the pressure plate 28 between its ends forms a light but strong box-like structure offering substantial resistance to flexing under load. Moreover, the stiffening member 32 provides a foundation or platform to which the terminal fittings 9 of the link members 5 are fixedly secured preferably by means of short spacing members 35 disposed between and secured to the stiffening plate 32 and the anchor members 9 at the respective opposite ends of the link members 5.

In accordance with this invention also, means are provided at each end of the rubbing head for readily releasably securing the layer 31 of rubbing material to the rubbing head. The embodied securing means is designed to hold the rubbing material securely in substantially taut fashion between the ends of the shoe while enabling it to be replaced quickly for replacement by a simple yet fast-acting fastening device. One such fastening means is disposed at each end of the rubbing shoe, the fasteners being identical in construction, mounting and arrangement and as here preferably embodied each comprises an actuating lever member 36 mounted between and upon brackets 37 fixedly secured to the stiffening plate 32, for pivotal movement on bearings 38 toward and away from the latter. Side flanges 39 of the lever member 36 provide pivot bearings 40 for the respective opposite ends of a spring-wire retaining member 41 which is preferably substantially coextensive in width with the pressure plate 28 and is adapted to be lodged substantially snugly in the pocket or recess 30 formed by each in-turned end portion of the pressure plate, as is best shown in Figure 2. The position of the pivot bearings 40 in the side flanges 39 is one ensuring that in the locked position of the actuating lever member 36, as shown in Figure 2, the axis of the co-axial bearings 40 will lie between the pressure plate 28 and the inclined equilibrium reference plane connecting socket 30 with the axis of the bearings 40. It will be apparent that, as the right hand lever member, for example, in Figure 2 is rotated in a counter-clockwise direction, the distance between the axis of the bearing 40 and the base of the socket 30 will be shortened, thus placing the spring-wire retaining member 41 under further compression until the rotational axis of bearing 40 lies in the equilibrium reference plane. Further rotation will result in the compressed spring-wire member suddenly forcing the lever member through a substantially greater angle into fully released position, permitting the spring member to be disengaged entirely from the locking recess for replacing the rubbing material. The reverse operation will result in an automatic snap-action locking of the spring member in position as the bearing points move past the reference plane in a clockwise direction as viewed in Figure 2. A layer 42 of soft rubber or other suitable resilient material is preferably bonded to the under surface of the pressure plate so as to obtain a more uniform distribution of the rubbing pressure in operation.

In the operation of the embodiment of this in-

vention shown in Figures 1 to 5 inclusive, as an attachment for portable electric drills, the rotation of the counterpoise crank member 10 by the drill motor through the torque applied to the stub shaft 11 will result in the rubbing shoe 2 being set in a high speed motion of circular translation in the plane of the rubbing face. As previously noted, the "throw" of the crank pin 12 is desirably large, e. g. one quarter inch, in order to obtain a high rubbing speed in the orbit of movement. It will be apparent, however, that the highly flexible link members will offer little resistance to flexure, thus placing substantially no objectionable load on the power unit from this cause. At the same time, there can be no relative rotation of the rubbing shoe relative to the power unit and there is hence no overstressing of the stabilizing link members as would occur were stress due to deflection in rotation added to that due to vibration. Moreover, the exertion of greater rubbing pressure on one end of the rubbing shoe than on the other cannot result in a stopping or diminishing of the extent of sideways motion of the end at which the pressure is increased. Such a change would impose undesirably heavy loads on a low power hand drill were the change permitted since a stopping of the sideways motion of the toe for example would double the sideways motion of the heel, thus doubling the flexural stress. No such action is possible with the flexible pantograph stabilizing means of this invention. It will also be apparent that by reason of the construction of the stabilizing means, the parts will require no oiling except for the bearing unit and the presence of abrasive materials will not result in wear of the stabilizing members, whose life is for all practical purposes, infinite.

In Figure 6 there is depicted a modified form of eccentric connection between the crank member 10 and rubbing shoe 1. The construction serves further to reduce the vertical spacing between the centers of mass of the eccentric portion 13 of the crank member and of the rubbing shoe along the rotational axis of the stub shaft 11, thus further reducing the couple action therebetween and obtaining a closer approximation to complete dynamic equilibrium. As shown, the crank member 10 is recessed to receive the bearing unit 14 which fits over a generally cylindrical pin 43 having an annular mounting flange portion 44 fixedly secured with reference to the rubbing shoe between the stiffening plate 32 and the pressure plate 28. The crank action remains the same as in the embodiment of Figure 2, but the placing of the counterweight portion closer to the rubbing head reduces the magnitude of the couple tending to whip the shaft 11 and subject the bearings of the prime mover 17 to side thrust.

The invention in its broader aspects is not limited to the specific mechanisms shown and described but departures may be made therefrom within the scope of the accompanying claims without departing from the principles of the invention and without sacrificing its chief advantage.

What is claimed is:

1. A rubbing device for attachment to hand drilling machines having a drill body, said device comprising an attaching head having an opening to receive said drill body and adapted to be releasably clamped to the drill body; a rubbing head; an intermediate rigid frame element between said attaching head and said rubbing head; separate sets of flexible link members flexibly

connecting said intermediate frame element to said rubbing head and to said attaching head, respectively, the link members of the respective sets being parallel to each other and the link members of one set being at substantially right angles to the link members of the other whereby translatory but not rotary motion of said rubbing head relative to said attaching head is permitted; and, a crank member to be connected to and rotated by the driving shaft of said drilling machine for imparting motion to said rubbing head said crank member being journaled to said rubbing head on an axis eccentric to the axis of said driving shaft when the drilling machine is in said opening.

2. A rubbing device for attachment to hand drilling machines having a drill body, said device comprising an attaching head having an opening to receive said body and adapted to be releasably clamped to the drill body; means on said attaching head movable into and out of a fixed position of engagement with said body for clamping said head to said body; a rubbing head articulated to said attaching head by separate link systems each comprised of parallelly extending flexible strips; a crank member to be removably connected to said drilling machine for rotation thereby, said member having journal engagement with said rubbing head substantially at its center-of-gravity on an axis eccentric to the rotational axis of the crank and having a counterweight portion for statically and dynamically balancing said rubbing head relative to said rotational axis.

3. The device comprising a live frame; a dead frame; an intermediate frame; a system of parallelly extending flexible strips connecting said intermediate frame to said dead frame; a separate system of parallelly extending flexible strips connecting said intermediate frame to said live frame, the strips of each said system being adapted to yield in directions normal to the plane of said live frame and the strips of one said system being disposed at substantially right angles to the strips of the other; and, means to be rotated on an axis fixed relative to said dead frame for imparting a gyroscopic motion to said live frame, said means being journaled to said live frame on an axis eccentric to said fixed axis.

4. A rubbing device for attachment to portable drilling machines comprising an attaching head having an aperture through which said machine is adapted to be inserted; movable clamping means carried by said head for fixedly securing said machine in said aperture to said head; a rubbing head articulated to said attaching head by separate link systems each comprised of parallelly extending flexible strips; and, means to be removably attached to and driven by said machine, for actuating said rubbing head.

5. A rubbing device for attachment to hand electric drilling machines having a body provided with a handle end and a driving shaft end, said device comprising an attaching head adapted to encompass the body of said drilling machine between its handle end and its driving shaft end; clamping means for releasably securing said head to said body in a determined fixed position between said ends; a rubbing head having a journal bearing located centrally thereof; a crank member having a stub shaft adapted for operative engagement with and rotation by the driving shaft of said machine on an axis eccentric to the rotational axis of said journal bearing and fixed relative to said attaching head, said crank member having a crank pin journaled in said journal

11

bearing and having a counterweight portion closely adjacent the rubbing head substantially in the plane of said bearing for statically and dynamically balancing the rubbing head about the rotational axis of said stub shaft; an intermediate frame disposed substantially midway between said heads; a set of parallel flexible strips connecting said frame to said attaching head; and, a separate set of parallel flexible strips at right angles to said first mentioned set connecting said frame to said rubbing head; whereby a gyratory motion may be imparted to said rubbing head by said drilling machine while rotation of said rubbing head relative to said attaching head is prevented.

6. A device for attachment to hand electric drilling machines having a body provided with a handle end, a driving shaft end and ventilating apertures intermediate said ends, said device comprising an attaching head adapted to encompass the body of said drilling machine in a determined fixed position between its handle end and its driving shaft end; means on said attaching head movable into and out of a fixed position of engagement with said ventilating apertures in said determined fixed position of said attaching head on said body, for clamping said head to said body; a movable head carried by said attaching head; and, means to be removably attached to and driven by said machine for actuating said movable head.

7. In the combination of an electric motor and a rubbing device, the improvement comprising an attaching head connected to said motor; a rubbing head; an intermediate rigid frame element between said attaching head and said rubbing head; separate sets of flexible link members flexibly connecting said intermediate frame element to said rubbing head and to said attaching head, respectively, the link members of the respective sets being parallel to each other and the link members of one set being at substantially right angles to the link members of the other whereby translatory but not rotary motion of said rubbing head relative to said attaching head is permitted; and, a crank member to be connected to and rotated by the driving shaft of said electric motor for imparting motion to said rubbing head, said crank member being journaled to said rubbing head on an axis eccentric to the axis of said driving shaft.

12

8. A rubbing device in accordance with claim 4 wherein the movable clamping means for securing the drilling machine to said attaching head include means movable into and out of a fixed position of engagement with the ventilating apertures present on said drilling machines.

9. A rubbing device for attachment to hand drilling machines having a drill body, said device comprising an attaching head having an opening to receive said drill body and adapted to be releasably clamped to the drill body; a rubbing head; an intermediate rigid frame element between said attaching head and said rubbing head; separate sets of link members flexibly connecting said intermediate frame element to said rubbing head and to said attaching head, respectively, the link members of the respective sets being parallel to each other and the link members of one set being at substantially right angles to the link members of the other whereby translatory but not rotary motion of said rubbing head relative to said attaching head is permitted; and, a crank member to be connected to and rotated by the driving shaft of said drilling machine for imparting motion to said rubbing head, said crank member being journaled to said rubbing head on an axis eccentric to the axis of said driving shaft when the drilling machine is in said opening.
